(57) CLAIM

The ornamental design for a tumbler with sleeve and lid, as shown and described.

DESCRIPTION

FIG. 1 is a perspective view of a tumbler with sleeve and lid showing our new design;

FIG. 2 is a front view thereof;

FIG. 3 is a right side view thereof;

FIG. 4 is a rear view thereof;

FIG. 5 is a left side view thereof;

FIG. 6 is a top view thereof;

FIG. 7 is a bottom view thereof;

FIG. 8 is an exploded view thereof; and,

FIG. 9 is a cross-sectional view of the tumbler with sleeve and lid taken along line 9-9 of FIG. 6.

The broken lines in the figures are for environmental purposes only and do not form any part of the claimed design.
